UNITED STATES PATENT OFFICE

2,531,385

ELECTRIC IMMERSION HEATER

Herbert L. Barnebey, Richmond Township, Allegheny County, Pa., assignor to Blaw-Knox Company, Pittsburgh, Pa., a corporation of New Jersey

Application December 23, 1948, Serial No. 66,892

16 Claims. (Cl. 219—38)

1

This invention relates to an electric heater with a bare resistance heating element suitable for immersion in the vaporizing material in a vapor heating jacket surrounding the bottom of a processing vessel. More particularly, this invention relates to spacing lattices for insulating and supporting electric ribbon resistors arranged in banks of loops to provide efficient and quick heat input of great magnitude to the vaporizing substance in the jacket without decomposing that substance or interfering with its circulation through the heater and without danger of short-circuiting.

In the heating of reaction vessels, such as those used in the varnish and resin industry, by means of vapor jackets, electric immersion heaters are used which extend into the jacket below the normal level of the pool of vaporizing liquid therein. While formerly such immersion heaters included a heating element encased in a layer of insulating material, a heating lag and a severe limitation on the heating capacity were introduced which adversely affected the efficiency of the operation. Subsequently, it became common to use bare resistor heaters immersed in the vaporizing liquid or substance, usually one of an organic nature such as "Dowtherm" which does not readily decompose under extreme heating demands. The bare resistors used often comprised a conventional type of nickel-chrome electric resistance conductor alloy such as "Nichrome".

When it is considered that commercial installations employing such vapor heating jackets with electric immersion heaters may require a power input in excess of 300 kilowatts, it is at once realized what a problem it is to provide a structure which will quickly and safely enable heat inputs of such magnitude to be made and sustained. The solution of this problem involves the available voltage and power, the permissible size and height of the reaction vessel and jacket, the material to be treated and the other economic, physical and structural considerations present. In one case, the necessary heating input is obtained by a novel design of arcuate immersion heaters in a horizontal oblique arrangement with looped ribbon resistors on edge in banks therein. Such a construction is generally shown and claimed in United States patent No. 2,434,016 issued January 6, 1948, the application for which was copending with the applicant's pending United States application Serial No. 656,570 filed March 23, 1946. The instant application is a continuation-in-part of the latter application S. N. 656,570 which was later abandoned.

2

By the provision of the insulating lattices in combination with resistors of this invention, the applicant has produced in an electric immersion heater a compact structure which enables the respective banks of resistors, whether in ribbon form or otherwise and whether on edge or otherwise, to be quickly and easily looped back and forth in each bank and assembled both when the heater is new and whenever any replacement or repair may be in order. At the same time, this invention provides a multitude of vertical passages for the easy circulation of vapors and vaporizing substance past the resistance heating elements while maintaining appropriate distances between adjacent banks and adjacent portions of the loops in each bank of the elements in a positive manner by means of the lattice-work insulators. Moreover, the various parts used in constructing the interlocking but somewhat loosely fitted together lattices are made of uniform slender sections and of relatively inexpensive material. Irregular shaped sections have unequal thermal deformation and are subject to internal stresses in heating and cooling which cause breakage of parts. The heater of this invention employs rods or rods and plates of generally uniform section which do not develop such stresses in service. These sections furthermore are replaceable without complete disassembly of the heater and should breakage occur in handling, a broken part can be removed and a new one inserted without difficulty. Each part is free to contract or elongate due to temperature changes without imposing undue or unsafe stress in companion members. Still further, the parts of the lattices are so constructed that they facilitate the operation of winding the unit with conductor ribbon resistor in banks.

This invention also provides a novel form of corrugated ribbon resistor with lanes in each lattice insulated from adjacent lanes for the loops in each bank, whereby the user optionally may obtain greater heating capacity per unit length of heater or a shorter length of heater for a given heat input rate. In this way, the provision of curved heaters for requirements of greater magnitude can on occasion be accommodated by a straight heater. Other objects and advantages of this invention will appear from the following description and the accompanying drawings, which are illustrative only, in which

Figure 1 is a central vertical section through the lower portion of a processing vessel having a vapor heating jacket therearound equipped with

immersion heaters constructed in accordance with one embodiment of the invention;

Figure 2 is a partial horizontal section taken along line II—II of Figure 1;

Figure 3 is a plan view of one of the immersion heaters in Figure 2 removed from the jacket;

Figure 4 is an elevational view of the closure plate by means of which such a heater is mounted in the jacket;

Figure 5 is a vertical section through the terminal or outer end of such a heater taken along line V—V of Figure 3;

Figure 6 is a partial section taken along line VI—VI of Figure 4 showing the manner of mounting the terminal box at the terminal end;

Figure 7 is a transverse section through the heater taken along line VII—VII of Figure 5;

Figure 8 is a transverse section taken along line VIII—VIII of Figure 3 showing the insulating spacer lattices on an enlarged scale;

Figure 9 is a side elevation of the inner end of the heater;

Figure 10 is an end view of the inner end of the heater with the insulating spacer lattices and resistors omitted;

Figure 11 is a plan view of a heater constituting the preferred embodiment of this invention;

Figure 12 is a side view of the heater shown in Figure 11, with the nearer spaced side bar broken away to show the terminal ends of the corrugated ribbon resistors;

Figure 13 is a view in cross section taken along line XIII—XIII of Figure 12;

Figure 14 is a view in cross section taken along line XIV—XIV of Figure 12;

Figure 15 is an enlarged view of the common electrical bus connection shown in Figure 13 for the ends of the resistors in the respective banks of the heater; and

Figure 16 is a side view of the electrical bus connection shown in Figure 15.

Referring now in detail to the drawings and, for the present, to Figures 1 and 2 particularly for one embodiment of this invention, a processing vessel 10 has a vapor heating jacket 11 surrounding the bottom and lower portion thereof and adapted to contain vaporizable liquid to a level in the neighborhood of the chain line 12. The vessel 10 has a bottom discharge port 13 adapted to be closed by a suitable valve (not shown). The jacket 11 has a central passage 14 in alignment with the port 13. The side wall of the jacket 11 has a plurality of circumferentially spaced ports 15 having their centers substantially in a common horizontal plane intermediate the bottom of the vessel 10 and the bottom of the jacket. Necks 16 extend outwardly from the ports 15. These may be simply pieces of pipe of suitable length welded in the ports and having a coupling flange on the outer end. As shown in Figure 2, the necks 16 are disposed at an oblique angle to the radii of the jacket through the centers of the ports. A heater indicated generally at 17 is inserted through each neck 16. The heaters may be straight but in the embodiment shown are preferably curved in the horizontal plane to the general form of a spiral and terminate at points spaced from the passage 14. A collecting shell or funnel 18 is supported in the jacket 11 between the heater 17 and the bottom of the vessel 10 by radial plates 19. The shell has a central opening 20, the edge of which is spaced from the wall of the passage 14. The funnel thus serves to collect condensate dropping from the outer

surface of the vessel 10 and deliver it adjacent the inner ends of the heaters 17.

The details of construction of the heaters 17 are shown in Figures 3 through 10. Each heater comprises a horizontal elongated frame including side bars 21 secured to a closure plate or base 22 in the form of a disc adapted to be bolted to the coupling flange on the neck 16. The bars are secured together at their inner ends by through bolts 23 having spacer sleeves 24 thereon. Insulating spacer lattices 25 are carried by the bars 21 transversely thereto and in spaced relation therealong. As shown in Figure 8, the lattices include vertical separator rods 26 of oval shape in section disposed side-by-side and having transverse registering holes spaced therealong through which round transverse supporting rods 27 extend. The fit of the rods 27 in the holes is relatively loose rather than snug, to permit sufficient independent movement of the rods in case of differential expansion or contraction. The rods 26 and 27 are composed of glass, porcelain, or the like, and are assembled in interlocking relation to constitute the respective lattices. The intermediate rods 27 extend into holes in the bars 21 registering with the corresponding holes through separator rods 26 but terminate short of the outer surfaces thereof. This provides freedom for slight movement of the rods. The top 30 and bottom supporting rods 27 as well as the other supporting rods 27 are retained in position by clamping straps 28. The straps are secured to the bars by bolts 29 and have their ends bent over to enter notches 27' at the ends of the uppermost and lowermost rods 27 with a slight clearance therebetween. While the uppermost supporting rods 27 in each heater 17 may not carry the weight of a conductor, as the structure is symmetrical and reversible and may optionally be installed with either side down, it is obviously desirable that all the rods be adapted to act as supports. In any event they function to form with the respective separator rods 26 laterally and vertically extending conductor enclos- 45 ing cells in each lattice 25. These cells in each lattice are substantially in axial registry with the cells of the lattice or lattices adjacent thereto. These closed cells in the form of rectangles generally, are constructed large enough to accommodate the particular cross section of the resistor that is employed and to allow sufficient clearance for such differential movement as may occur upon the heating and cooling of the resistance element. Thus, the resistance elements are held in substantially vertical and horizontal alignment in each heater 17, separated horizontally by the separator rods 26 and vertically by the supporting rods 27.

A ribbon or strip resistance conductor 30 is 60 wound in lengthwise loops, back and forth longitudinally of the frame and in three vertically spaced banks, the adjacent loops being spaced apart by the vertical separator rods 26 and the several banks by the horizontal supporting rods 65 27. The conductor is bare and constitutes the resistance heating element of the heater. It is composed of a metal having suitable resistance and durability such as the well known nickel-chromium alloy. Each bank of loops is actually 70 formed by a separate piece of conductor strip, the adjacent ends of the several strips being connected in series by vertical lengths of strip 31, that connecting the upper two banks being depicted in Figure 3, and that connecting the lower two banks being depicted in Figure 5.

The construction of the lattices 25 described above facilitates the winding of the several strips forming the conductor 30 in back and forth loops. For this purpose, the uppermost rods 27 of the lattices are removed and the strip which is to form the intermediate bank of loops is laid in the spaces between the rods 26. The uppermost rods 27 are then replaced and the next lower rods 27 are removed. The intermediate bank is then pushed downwardly to its final position and the rods 27 thereabove replaced. Thereafter the uppermost bank is wound in the same way. The heater is then turned over and the lowermost bank is similarly wound. It is to be noted that resistor strips 30 have a minimum area of contact with separator rods 26 and a maximum area of vertical passage for contact with the vaporizing substance.

The outer ends of the conductor ribbons forming the top and bottom banks of loops are connected to vertically spaced terminal posts 32 extending through the closure plate 22. Each terminal post 32 has an integral flange 33 intermediate its ends and spools 34 and 35 adjacent the opposite ends adapted to cooperate with clamping nuts turned on the extreme ends of the posts which are threaded to receive them. Split insulated bushings 36 surround the posts between the flange 33 and the spools 34 and 35. Insulating rings 37 are disposed on both sides of the flange 33. Each post is fixed in position on the closure plate 22 by a clamping block 38 secured thereto by studs 39. The closure and blocks are suitably recessed to accommodate the flange 33 and rings 37. Sealing gaskets are disposed between the closure plate 22 and the inner ring 37, between the blocks 38 and the outer ring 37, and between the flange 33 and the two rings on opposite sides thereof to prevent any leakage of heating vapor. The two terminal posts 32 are in vertical alignment and the ends of the conductor ribbon strips connected thereto are bent and twisted slightly as shown in Figure 3 to make contact therewith. In Figure 3, the end of the conductor strip forming the bottom bank of loops is broken off short of its terminal post 32 to avoid obscuring the showing of the manner of attachment of the uppermost strip 30 to the post.

A cylindrical terminal box 40 is secured to the closure 22 by studs 41. The outer face of the closure has a circular groove 42 adapted to accommodate the inner edge of the box. A cover 43 is removably secured to the outer end of the box by studs 44. A tapped hole 45 is provided at the bottom of the box for the connection of a conduit through which suitable electrical conductors from a direct current or single phase power source extend to the outer ends of posts 32.

In a preferred embodiment of this invention, illustrated in Figures 11 to 16, inclusive, an electric immersion heater 50 comprises a horizontal elongated frame having spaced side bars 51 rigidly attached to a closure plate or base 52 which serves the same purpose as base 22 in the embodiment earlier described. Bars 51 are secured together at their inner ends by through bolts 53 having spacer sleeves 54 thereon. A lattice-work insulator comprising a plurality of insulating spacer lattices 55 are carried by and between bars 51 transversely thereto and in spaced relation therewith. Each lattice 55 includes a plurality of parallel vertical separator strips 56. Strips 56 are positioned between bars 51 in substantially parallel relation thereto and define a plurality of parallel lanes between the said bars. Lattices 55

also include a plurality of horizontally positioned supporting rods 57 which are inserted through transverse registering holes in side bars 51 and separator strips 56. These transverse registering holes are provided in vertical planes transverse to bars 51 at spaced intervals therealong, said vertical planes coinciding with the longitudinal spacing of lattices 55. The axes of the transverse registering holes are located at right angles to separator strips 56 and the holes are sufficiently larger than supporting rods 57 to allow for movement of supporting rods 57 in the event of any differential expansion or contraction. For the same reason, those of the rods 57 which pass through bars 51, as shown in Figure 14, terminate somewhat short of the outer surfaces thereof.

Separator strips 56 and supporting rods 57 are composed of insulating material such as glass, porcelain or the like, and are assembled in interlocking relation to constitute the series of lattices 55, each of which defines a plurality of closed cells in parallel lanes in axial or longitudinal alignment with the cells and parallel lanes defined by the immediate lattice or lattices 55 on each side. Separator strips 56 may extend, as shown in Figure 11, for a length of more than the distance between adjacent lattices 55, or each strip may extend midway between lattices. Vertically, the strips 56 may cover the entire depth of the heater 50 as shown in Figure 13 or separate strips may be provided for each bank and be substantially positioned one atop the other, edge to edge. Outermost strips 56, like outermost rods 26, are slightly shorter than the intermediate strips 56 and uppermost and lowermost supporting rods 57 rest thereon. These uppermost and lowermost rods 57, which serve the same purpose as the uppermost and lowermost rods 27 in the other embodiment described in this invention, are notched at 57' for reception respectively of the bent ends of clamping straps 58. These straps are secured to side bars 51 by bolts 59 as illustrated in Figure 14. There is sufficient clearance between clamping straps 58 and the various adjacent portions of the lattices 55 to permit such expansion as may take place during operation.

The preferred embodiment of this invention is particularly applicable in those situations in which the heat inputs or the voltages used are so great or in which the nature of the resistance element or vaporizing substance is such that more positive insulation of the lanes in each bank, is desirable. Such insulation is provided by separator strips 56 which have a sensible thickness across the width of the heaters. Hence, it is desirable to keep such lanes, which are parts of the respective lattices 55, defined and the strips 56 separated so vapors and the vaporizing liquid can properly circulate in the course of operations. In this preferred embodiment a ribbon or strip resistance conductor 60 is provided which resistor is horizontally corrugated, that is, the sinusoidal bends forming the corrugations appear on a trace on a horizontal plane. Such a horizontally corrugated ribbon resistor 60 is wound with the corrugations remaining therein, in lengthwise loops, back and forth longitudinally, between side bars 51 with each portion of each loop in each vertically spaced bank, of which there are three positioned in a continuous lane formed by the aligned lattices 55. The banks themselves are spaced apart and insulated from each other by the horizontal supporting

rods 57, in the same way that the banks of the earlier described embodiment are insulated from each other by supporting rods 21. Resistor 60 constitutes the bare resistance heating element of heaters 50 and is composed of a suitable metal alloy as that described in connection with resistor 30. A separate length of resistor 60 is used for each bank and the outer or terminal ends of each thereof on one side, as shown in Figure 13, are extended and bent for respective clamping engagement on terminal posts 62, each of which in character and mounting is substantially the same as the terminal posts 32 described in connection with the other embodiment. Because the preferred embodiment in Figures 11 to 16 is adapted to be energized by a 3-phase electrical power source system, a single electrical bus connection 61 is used to connect ends not connected to terminals 62 of the resistor 60 in the respective banks. Bus connection 61 comprises a back strip 61a and a clamping strip 61b which is fastened to back strip 61a by machine screws 61c. These machine screws pass through corresponding holes in the non-terminated ends of the respective resistors 60 to connect all of them electrically as shown in Figure 13 and thus complete the heating circuit. The mode of assembly of lattices 55 and resistors 60 is substantially the same as that described for lattices 25 and resistors 30.

Further, by the use of resistors 60 with the corrugations, a much greater length ribbon may be wound on a frame of given length, which permits either shorter frames or lower heating rate per ribbon area for a given heat input. Assuming the heating rate need not be lowered but that the frame for a given heat input may be shortened, for many services the heaters need not be curved but can be wholly straight and placed in an oblique arrangement tangential to an inscribed circle of lesser diameter than the inside outer diameter of the jacket and concentric therewith. In some cases the saving in length for a given heating capacity will be so great that the heaters 50 can be mounted in the jacket in horizontal radial fashion. Such a foreshortening of the length of the heaters is made possible by the increase in the effective area of contact obtained between the vaporizing substance and the resistors. In other instances, using liquids which may decompose if the heating rate per ribbon area is high, the use of corrugated ribbons increases substantially the heating surface area of the ribbons which can be wound in a given frame and makes such lower heating rates practicable with the accompanying longer life of the liquid.

Although I have illustrated and described a preferred embodiment and a modification of my invention, it will be recognized that changes in the structural details and arrangement thereof may be made without departing from the spirit of the invention or the scope of the appended claims.

I claim:

1. In an electric immersion heater, in combination, a supporting member, a lattice-work insulator extending along and supported by said member, said insulator having a plurality of lattices therein at spaced intervals, each lattice being formed of a plurality of parallel insulating separators and a plurality of parallel insulating rods, said separators and said supporting rods being disposed substantially at an angle to each other and adapted to supportably engage each

other with space for differential thermal movement therebetween and to form a plurality of closed cells in each lattice, said closed cells and their respective openings being in substantial axial registry with such cells and their respective openings in an adjacent lattice, and a resistor looped back and forth through said cells and openings.

2. In an electric immersion heater, in combination, a supporting member, a lattice-work insulator extending along said member, said insulator having a plurality of lattices therein at spaced intervals along the length thereof, each lattice being formed of a plurality of parallel insulating separators and a plurality of parallel insulating rods, said separators and said supporting rods being disposed substantially at right angles and adapted to supportably engage each other with space for differential thermal movement therebetween, said separators and said supporting rods further forming a plurality of closed cells in each lattice, said closed cells and their respective openings being in substantial axial registry with such cells and their respective openings in an adjacent lattice, said supporting rods being supported by said member, and a resistor looped back and forth through said closed cells and openings between said separators.

3. In an electric immersion heater, in combination, a supporting member, a plurality of rectangular insulator lattices supported by said member, said lattices being spaced along said member, each lattice having a plurality of closed cells therein extending laterally across said lattice, said closed cells and their respective openings being in substantial axial registry with such cells and their respective openings of an adjacent lattice, each lattice further having a plurality of parallel insulating separators placed side by side and a plurality of parallel insulating supporting rods, said separators and said supporting rods being disposed substantially at right angles to each other to form said closed cells and adapted to supportably engage each other with space for differential thermal movement therebetween, and a resistor ribbon looped back and forth on edge through said closed cells and openings between said separators.

4. In an electric immersion heater, in combination, a substantially horizontal elongated supporting member, a plurality of rectangular insulator lattices supported by said member, said lattices being spaced along said member and transverse thereto, each lattice having a plurality of closed cells therein extending laterally across said lattice, said closed cells and their respective openings being in substantial registry with such cells and their respective openings of an adjacent lattice, each lattice further having a plurality of parallel insulating separators and a plurality of parallel insulating supporting rods, said separators and said supporting rods being disposed substantially at right angles to each other to form said closed cells, said supporting rods being disposed in a vertical plane and adapted to support said separators with space for differential thermal movement therebetween, said supporting member and said separators having a plurality of registering holes in a series of vertical planes spaced along the length of said supporting member through which said supporting rods are respectively inserted, a resistor ribbon looped back and forth on edge on said supporting rods through said closed cells and openings between

said separators, and terminals at the ends of said resistor ribbon through which the energization of said resistor ribbon is effected.

5. In an electric immersion heater, in combination, a supporting member, a plurality of rectangular insulator lattices supported by said member, said lattices being spaced along said member, each lattice having a plurality of closed cells therein extending laterally and vertically across said lattice forming a plurality of banks, said closed cells being in substantial axial registry with such cells of an adjacent lattice, each lattice further having a plurality of parallel insulating separators placed side by side and a plurality of parallel insulating supporting rods, said separators and said supporting rods being disposed substantially at right angles to each other to form said closed cells and adapted to supportably engage each other with space for differential thermal movement therebetween, and a resistor ribbon in each bank looped back and forth on edge on said supporting rods through said closed cells between said separators.

6. In an electric immersion heater, in combination, a plurality of spaced elongated side bars, a plurality of rectangular insulator lattices supported by said side bars, said lattices being spaced along the length of said side bars and transverse thereto, each lattice having a plurality of parallel insulating separators placed side by side and a plurality of parallel insulating supporting rods, said separators and said supporting rods being disposed substantially at right angles to each other to form a plurality of closed registering cells through said lattices, said supporting rods extending through registering holes in said side bars and through said separators and adapted to support said separators with space for differential thermal movement therebetween, clamping means positioned adjacent said side bars to hold said supporting rods in assembled position, said supporting rods further fitting loosely into said registering holes and between said clamping means, a resistor ribbon looped back and forth on edge on said supporting rods between said separators, and terminal means for energizing said resistor ribbon.

7. In an electric immersion heater, in combination, a supporting member, a plurality of rectangular insulator lattices supported by said member, said lattices being spaced along said member and transverse thereto, each lattice having a plurality of closed cells therein extending laterally and vertically across said lattice forming a plurality of banks, said closed cells being in substantial axial registry with such cells of an adjacent lattice, each lattice further having a plurality of parallel insulating separators placed side by side and a plurality of parallel insulating supporting rods placed in a vertical plane, said separators having a greater dimension in the direction of the length of said supporting member than the dimension transverse thereto, said supporting member and said separators having a series of registering holes in a vertical plane therethrough spaced along the length of said supporting member and adapted to have said supporting rods inserted therein, a resistor ribbon looped back and forth on edge on said supporting rods in each bank through said closed cells between said separators, and terminals for said resistor ribbon through which the energization thereof is effected.

8. In an electric immersion heater, in combination, spaced side bars, a plurality of lattices

spaced along said bars, each lattice including a plurality of parallel separator rods of insulating material disposed side by side and a plurality of supporting rods of insulating material on which said separator rods are carried, said supporting rods being disposed transversely to said separator rods and engaging said side bars, said supporting rods being further disposed substantially in a vertical plane, and a resistor ribbon looped back and forth along and between said side bars with each side of each loop thereof being disposed between respective separator rods.

9. In an electric immersion heater, in combination, spaced side bars, a plurality of parallel separator rods of insulating material disposed vertically side by side between said bars, each of said separator rods having a plurality of transverse registering holes therethrough, each of said separator rods further having a greater dimension along the lengthwise direction of said spaced side bars than the dimension transverse thereto, a plurality of parallel supporting rods of insulating material adapted to be inserted through said transverse registering holes and to engage said side bars to support said separator rods, and a resistor ribbon looped back and forth on edge between said separator rods.

10. In an electric immersion heater, in combination, a horizontal elongated supporting frame member, a plurality of parallel separator rods of insulating material disposed vertically side by side and extending transversely of said frame member, each of said separator rods having a plurality of transverse registering holes therethrough, said registering holes being at right angles to each of said separator rods, each of said separator rods further having a greater dimension in the direction of elongation of said frame member than in the dimension transverse thereto, a plurality of parallel supporting rods of insulating material adapted to be inserted through said transverse registering holes and to engage said frame member to support said separator rods and complete a plurality of lattices, said lattices defining a plurality of banks of laterally adjacent cells, said lattices being in alignment with adjacent lattices, and a resistor ribbon looped back and forth on edge through each of said cells in each of said banks.

11. In an electric immersion heater, in combination, spaced horizontal elongated side bars, a plurality of parallel separator rods of insulating material disposed vertically side by side in a plurality of parallel planes spaced along and transversely between said side bars, said separator rods extending vertically beyond said side bars, each of said separator rods having a plurality of transverse registering holes therethrough at right angles to said separator rods, said side bars having holes therethrough registering with corresponding holes in said separator rods, a plurality of parallel supporting rods of insulating material adapted to be inserted through said transverse registering holes to complete a plurality of aligned lattices defining a plurality of banks of laterally adjacent closed cells, said supporting rods engaging said transverse registering holes extending through said side bars being adapted to support said lattices on said side bars, clamping straps extending vertically adjacent each end of said supporting rods in each lattice to hold said supporting bars in position, and a resistor ribbon looped back and forth on edge through each of said closed cells in each of said banks, said resistor ribbon being supported on said supporting

rods and having adjacent portions thereof insulated by said separator rods.

12. In an electric immersion heater, in combination, an elongated supporting frame member, a plurality of lattices supported by and spaced along said frame member transversely thereto, a plurality of parallel separator strips of insulating material adjacent said frame member and extending in the direction of its elongation, a plurality of parallel supporting rods of insulating material adapted to supportably engage said separator strips in a plurality of spaced parallel planes intersecting said strips to form said lattices with a plurality of closed cells and parallel lanes, said lanes extending between said spaced parallel planes, and a resistor threaded in loop fashion through said closed cells and back and forth in said lanes.

13. In an electric immersion heater, in combination, horizontal elongated supporting side bars, a plurality of lattices supported by and spaced along and between said side bars transversely thereto, a plurality of parallel separator strips of insulating material positioned on edge between said side bars and substantially parallel thereto, a plurality of parallel supporting rods of insulating material adapted to supportably engage said separator strips in a plurality of vertical spaced parallel planes intersecting said strips to form said lattices with a plurality of closed cells and parallel lanes, said lanes extending between said vertical spaced parallel planes, and a horizontally corrugated ribbon resistor looped back and forth on edge through said lanes with substantially each portion of each loop separated by said separator strips.

14. In an electric immersion heater, in combination, horizontal elongated supporting side bars, a plurality of parallel separator strips of insulating material positioned on edge between said side bars and substantially parallel thereto, a plurality of transverse registering holes through said side bars and said separator strips, said transverse registering holes being in a plurality of spaced vertical parallel planes between and transverse to said side bars, a plurality of parallel supporting rods of insulating material adapted to be inserted through said transverse registering holes to complete a plurality of insulating lattices between said side bars having a plurality of closed cells and parallel lanes, said lanes extending on each side of said closed cells substantially between said vertical spaced parallel planes containing said transverse registering holes, and a horizontally corrugated ribbon resistor looped back and forth on edge through said lanes.

15. In an electric immersion heater, in combination, horizontal elongated supporting side bars, a plurality of parallel spacer strips of insulating material positioned on edge between said side bars and substantially parallel thereto, a plurality of transverse registering holes through said side bars and said separator strips substantially at right angles to said separator strips, said transverse registering holes being in a plurality of vertical planes between and transverse to said side bars and spaced therealong, a plurality of parallel supporting rods of insulating material

adapted to be inserted through said transverse registering holes to support said separator strips and to complete a plurality of insulating lattices between said side bars, said lattices respectively having a plurality of closed cells and parallel lanes in a plurality of banks, said lanes extending on each side of said closed cells substantially between said spaced vertical parallel planes, a clamping strap adjacent said side bars and the ends of said supporting rods in each said vertical spaced parallel plane to hold said supporting rods in supporting position, and a horizontally corrugated ribbon resistor looped back and forth on edge through said closed cells and said lanes and occupying substantially the entire horizontal distance between said strips.

16. In an electric immersion heater, in combination, an elongated frame including a pair of spaced lateral beams each having an upper series and a lower series of holes spaced therealong, the said upper and lower series of holes each lying in a substantially horizontal plane and the holes in opposite lateral beams being in alignment, a plurality of insulating supporting rods extending across said frame from beam to beam each rod reposing at its ends in said holes, generally vertically disposed separator members of insulating material spaced along said rods, each of said separator members extending above and below the horizontal planes of said holes in said beams and having aligned holes therein through which said rods pass and support said separator members, the said separator members having other aligned holes adjacent their upper and lower extremities, closure rods extending across said heater through said other holes in said separator members, the interlocking separator members, supporting rods and closure rods comprising lattices with aligned cells in a plurality of generally horizontal banks spaced longitudinally along said frame, a resistor ribbon looped back and forth through the cells of each bank, and removable means on the sides of the frame closing said holes in said beams and in said separator members adjacent the ends of said supporting rods and said closure rods, whereby when said removable means are removed the cells of the outer banks may be opened by withdrawing said closure rods for insertion or removal of a resistor ribbon winding, and by removal of the set of supporting rods in either said upper or lower series of holes a resistor ribbon winding may be transferred relatively an inner bank without disturbing the balance of said frame and lattices.
